POWER-DRIVEN CUTTING MACHINE FOR
SHOULDER PADSLouis Alfandari, Corona, N. Y., assignor to L.
Alfandari Machine Co., Inc., Corona, N. Y.

Application April 29, 1948, Serial No. 23,880

6 Claims. (Cl. 164—62)

1

This invention relates to new and useful improvements in power driven cutting apparatus, and, more particularly, aims to provide a novel and valuable cutting machine incidental to the operation of which an article, to be subdivided by a cutting stroke, is manually placed in a receptor, there retained during the cutting stroke, and manually removed after completion of such stroke.

As the invention is herein shown, it is applied to a machine for making fillers for shoulder pads. As is well known, shoulder pads are generally triangular in outline, and a practice in making the fillers for such pads is to subject a substantially square mass of quilted, matted or plural-layer softly flexible material to a single cut diagonally of the square to produce two like substantially triangular fillers each for a different shoulder pad.

Said cut must be quickly and cleanly made, and desirably by a circular cutting knife power driven at high speed. A disadvantage, and indeed a serious danger, which it is the object of the present invention entirely to obviate, has been the chance of the knife cutting the fingers or hand of the attendant, during the cutting operation, or during the placement of said mass in position for being cut, or during the removal of the cut parts.

By the present invention, a receptor is provided for said mass, which receptor is mounted for movement toward and away from the attendant, under control of the latter; in combination with a placement of the field of operation of the cutting knife such that, with said knife under continuous drive from a power source, it is impossible for the attendant accidentally to become injured by the knife. The arrangement is such that when the receptor is positioned for receiving the material to be worked on, or for removing therefrom such material, either before or after having been worked on, the receptor is between the attendant and said field.

Preferably, according to the invention, the receptor is an open-top box, with a hinged lid, and slidably mounted for movement away from the attendant into a roofed-over housing at the field of operation of the cutting knife, and then, moreover, with said lid down over the top of the box. Thereby, with a circular knife, the cutting may be performed concurrently with the travel of the box into the housing and thence toward the far end of the latter. A treadle or the like may be used to reciprocate the box, and preferably in such way that a foot thrust on said

2

treadle is necessary to start the box toward and cause the box to make complete entry into the housing, and with a spring means or the like for acting automatically to return the box to its position immediately in front of the attendant on releasing the treadle from said thrust. In the latter connection, means are provided for readily adjusting the tension of said spring means.

Also, as the invention is preferably carried out, 10 with said lid hinged and normally spring urged to open position, a device is provided whereby when the lid is manually closed down over the top of the box, with the latter at its forward position and just after the attendant has placed 15 the material to be worked on in the box, the lid is latched closed; but, furthermore, to take care of the case where the attendant has neglected thus manually to close the lid, an arrangement is present whereby, almost at the instant the box 20 is started in its travel toward entry into the housing, the lid, if not closed, is slammed down.

Means are also provided whereby the spring 25 means for normally urging the lid to open position is easily varied in tension, to modify the force of the spring action.

Means are also provided whereby, when the 30 box is returned to its position in front of the attendant, following issuance of the box from the housing and so away from the field of operation of the knife, the aforesaid latch or the like 35 is automatically released, thereby causing the cover to fly up to a vertical position or there-beyond; and in the latter connection means are provided, preferably carried by the housing, for holding the lid in the position just-mentioned during all the while the box is directly in front of the attendant.

Further, means are provided whereby the 40 means for causing the cover to fly up as last described may be adjusted, in order to have such lid lifting occur at a point in the forward travel of the box best adapted for the convenience and celerity of motion of a particular attendant.

Various other features and advantages of the 45 invention will be pointed out or become apparent hereinafter.

For further comprehension of the invention, and of the objects and advantages thereof, reference will be had to the following description 50 and accompanying drawings, and to the appended claims in which the various novel features of the invention are more particularly set forth.

In the accompanying drawings forming a material part of this disclosure:

Fig. 1 is a perspective view, looking in a slightly

upward direction, of an embodiment of the invention as now favored.

Fig. 2 is a perspective view, looking down on the receptor, the housing, and the trackway guiding means for the receptor, and fragmentarily showing the table on which these parts are carried.

Fig. 3 is a top plan view of the receptor, with the lid closed.

Fig. 4 is a vertical section, taken through the machine on the line 4—4 of Fig. 2.

Fig. 5 is a detail view, being, on an enlarged scale, a section taken on the line 5—5 of Fig. 2.

Fig. 6 is, on a more greatly enlarged scale, a fragmentary perspective view; this view also being a section taken on the line 6—6 of Fig. 3.

Fig. 7 is a section taken on the line 7—7 of Fig. 6.

Fig. 8 is an enlarged detailed view similar to a portion of Fig. 4, but with the receptor in its nearly completely forward position.

Fig. 9 is a partial horizontal sectional view taken on the line 9—9 of Fig. 8.

Referring to the drawings more in detail, a table top 10 is suitably secured to and at the tops of a pair of end supporting structures each comprising an upper bracket 11 having two dependent slotted legs 12 and a lower skeletal casting 14 having feet 15 for resting on a floor. The four slots carried by the legs 12 provide, in combination with the bolts indicated and suitable apertures through the tops of the casting 14, a means for readily changing the level of the table top 10.

The lower skeletal casting has standards 14a. Each standard 14a has a cross member 16, to which members are suitably secured the opposite ends of a plate-like bar 17 for suspending as shown the motor 18. Also extended between the two standards is a tie-box 17a of L-shaped cross-section, and in which may be laid the main length of a cable 19 containing the wiring connections to the motor; this cable going to a switch 20. From said switch there is a cable 21 containing the wiring connections to a plug 22 for insertion in a nearby current supply receptacle.

The side of the table top 10 faced in Fig. 1 is that at which the attendant is positioned, either standing or on a suitable seat.

The cutting knife 23 is a circular one, fixed on a short shaft 24 carrying a pulley 25 and suitably journaled in and near the top of a columnar mounting 26 suitably secured to and upstanding from the bar 17; and also suitably secured to and upstanding from said bar is a bracket 27 on which is movably mounted a carrier 28 for a knife-sharpening grinding wheel 29, the arrangement being such that, with normally said wheel out of contact with the knife, a spider-like handle 30 may be manipulated to dispose the wheel 29 against the knife for sharpening the latter, then giving the knife a power driven rotation. The knife 23 is driven, in the direction of the arrow 31 of Fig. 4, by means of a belt 32, between the pulley 25 and a pulley 33 fixed on the motor shaft.

To the top casing of the motor 18 is suitably secured a rectangular plate 34, of sufficient width to have projecting marginal portions at opposite sides thereof. The suspension of the motor from the bar 17 is by way of said plate and a plurality of fairly long bolts, and nuts, as shown in Fig. 1, so that by use of different nuts, washers, collars or the like, as shimming or spacing elements

between the bar 17 and the plate 34, the motor may be raised or lowered relative to said plate, to effect a belt adjustment, as to take up slack therein.

The table top 10, for projection of the knife therethrough and up above the same substantially as best shown in Fig. 4, has a straight fore and aft extending slot 35. Parallelling this slot and for guiding a receptor 36 in its sliding movements are a pair of rails 38 here shown as being thin stock channels, arranged with their grooves facing each other.

The receptor 36 includes a rectangular bottom plate 39, opposite edge portions of which are slidably extended into the grooves of the channels 38. The plate 39 at its upper side and along its front and rear ends carries bars 40 and 41 secured thereto. The receptor 36 further comprises a lid 42, also in the form of a rectangular plate; four bars 43 outlining a diamond somewhat elongated laterally of the line of travel of the receptor, these bars 43 suitably secured to and upstanding from the plate 39; a hinging means for the lid and as a whole marked 44; four bars 45 outlining a similar but smaller diamond, these bars suitably secured to and dependent from the under side of the lid; and a means, including a pivoted latch member 46, for coacting with the swinging end of the lid for holding the lid closed.

The bottom plate 39 of the receptor is slotted as at 47, such slot being directly above the slot 35 through the table top 10; and above and in line with the slot 47 there is a space 48 between the adjacent ends of the two bars 43 which converge toward the bar 41 (see Figs. 2 and 3), a space 49 (see also Fig. 4) between the adjacent ends of the two bars 45 which converge toward the bar 41, and a slot 50 through said bar 41. When the lid 42 is down on the bars 40 and 41, the space 48 and the slot 50, these two always aligned with each other and with the slot 47, are also aligned with the slot 49.

The slots 35 and 50 and said spaces 48 and 49 are such, relative to the diameter and center of rotation of the knife 23, that said knife can have a cutting stroke through the material in the receptor, along the entirety of a central length of such material, in the direction of travel of the receptor 36, incidental to a movement of the receptor from its material feed-in and take-off position shown in Fig. 1, to its position shown in Fig. 4; it being understood in this connection that during said cutting stroke said material is lying flat in the diamond shaped pocket defined by the inner periphery of the diamond shaped structure provided by the bars 43, with said material squeezed down marginally thereof by the bottoms of the four bars 45.

The housing 51 overlying the field of operation of the knife 23 comprises side walls 52, 52, a back wall 53, and a roof wall 54. The housing 51 is open at its end facing the attendant, and the rails 38 extend through such opening.

For manual control of the back and forth sliding movements of the receptor 36, the bar 40 thereof has a recess 55, engaged by a finger 56 rigidly carried by and upwardly projected from the top of a lever 57 rockably mounted on a rod 58 secured at opposite ends to the casting 14. At the lower end of the lever 57 is a rod 59, having portions extended on opposite sides of the lever, so that either of these extended portions may be used as a treadle, to be pushed on by the heel-breast of a shoe worn by the attendant, thereby to swing the lever 57 from its normal position

(as in Fig. 1, and as shown in dot and dash lines in Fig. 4), to its full-line position in Fig. 4, to move the receptor 36 rearward to engage the contained pad with the knife 23.

As soon as said thrust on the treadle is released, the lever 57 effects automatic return of the receptor to normal position, by swing back of the finger 56 toward the attendant, thereby to withdraw the receptor from the housing 51 and advance the bar 40 of the receptor to the dot and dash location indicated at 40' in Fig. 4.

Said swing back of the lever 57 is effected by a coil spring 60, one end 61 of which (Fig. 1) is engaged with said lever, and the other end 62 of which is engaged with a neck 63 offset from a collar 64. This collar, which with the coiled central portion of the spring 60 embraces the rod 58, carries a set-screw 65; the neck 63 being tubular and internally threaded for taking said screw, and the latter being used to loosen its grip on the rod 58, for ready variation of the tension of the spring 60 by turning the collar 64 on the rod 58, and for then clamping the collar to hold the spring under the tension desired.

The latch member 46 is pivoted between a pair of offset ears carried by a bracket 66, see particularly Figs. 8 and 9, secured to the front side of the bar 40; said member 46 being shaped as best shown in Fig. 8, to provide a space for the accommodation of an expansile coil spring 67 to urge said member to the position shown in full lines in Fig. 4 and in Fig. 8, and to present a downwardly sloped tail 68.

The tail 68 of the latch member is for engaging a stop-bar 69, for arresting the receptor 36 when advanced to the limit of its travel toward the attendant. As the receptor completes this movement, the latch member 46 is engaged at its tail by the stop-bar, and the latch member is rocked, as indicated at 46' in Fig. 4, whereupon the receptor lid 42 is by a spring means associated with its hinge means swung up, as to the position indicated in Fig. 4 at 42', and there arrested by impingement against a pair of cushioned stop pieces 70 forwardly projected from a wall 71 atop the housing 51 and secured thereto as by way of an angle brace 72.

The stop-bar 69 is adjustable on the table 18 by means (Figs. 1 and 4) including a pair of slots 73 and 74 through the table, and bolt and nut elements as indicated at 75 and 76.

Referring now to the hinge means 44 for mounting the receptor lid 42, and particularly in this connection to Figs. 6 and 7 (with occasional cross references to Figs. 2, 3 and 4), a strip 77, as long as the bar 41 but only about half as wide, and of the same thickness as the lid 42, is suitably secured on said bar so as to provide a step 78. The hinge itself, this marked 79 in Fig. 7, is substantially of the same length as the bar 41.

The long pintle 80 of the hinge at each of two points spaced along its length, where pintle-engaging curls from the two hinge leaves are omitted, is sleeved by one of two like coil springs 81. The strip 77 is cut away to provide a recess, one thereof being indicated at 82, for each of said springs where the latter sleeves the pintle.

The spring 81 seen in Figs. 6 and 7 has at one end a straight offset portion 83 engaging an edge of the lid 42 and at its opposite end a straight offset portion 84. A slant-bottomed lateral recess 85 in the bar 41 always receives the spring portion 84, while a similar recess 86 receives the spring portion 83 when the lid is fully closed. The tension of the spring is such that were the lid

not present, the spring portion 83 would be forced to its position shown in Fig. 6 or therebeyond.

The other spring 81 is similarly constituted, and the bar 41 has, properly adjacent the last-named spring 81, recesses similar in form and function to the recesses 82, 85 and 86.

As shown best in Fig. 7, a headed screw 87 is threaded into a tapped hole through the bar 41 opposite the recess 85, for entry into that recess to engage the portion 84 of the spring there shown. Spiral advance of said screw may from time to time be effected, to increase the tension of said spring, so that always, at the instant already explained, the lid will be snapped up to the position 42' of Fig. 4. A similar tension adjustment for the other spring is also provided, the adjusting screw thereof being seen at 88 in Fig. 3.

All parts of the receptor are desirably made of metal, and to minimize elastic fatiguing of the springs 81, the lid 42 of the receptor and the lid carried bars 45 are preferably made of aluminum or an aluminum alloy. When the plate 38 of the receptor, and its bars 40, 41 and 43 are also made of aluminum or an aluminum alloy, this is advantageous also, as thereby a light weight and easily movable receptor is provided and one the treadle operation of which is not tiring on the attendant.

The attendant will be under instruction always to close the lid 42 for being caught by the latch member 46, before applying a forward foot-thrust to the treadle 59. Should the attendant forget, or be careless, the lid will be automatically closed by thrust thereagainst of the front edge of the roof wall of the housing 51, substantially simultaneously with the initiation of a travel of the receptor toward full entry into the housing.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a machine for cutting filler material for use in shoulder pads and having a table top formed with an elongated slot extended fore and aft of the table top and a continuously rotating disc knife fixedly mounted beneath the table top with a portion of its periphery extended upward through the back end of the slot, a slidably mounted receptor for carrying the filler material to be cut rearward to be engaged and cut by the knife, comprising rails mounted on the top face of the table top on opposite sides of the slot, a plate having its side edges slidably engaged in said rails to be slid rearward and forward relative to the knife and normally occupying the space between the knife and the front end of the slot, means for moving said plate rearward and forward, said plate being formed with an elongated slot aligned with the slot of the table top and extended from the rear edge of said plate to a point slightly rearward of the front edge of said plate, bars mounted on the top face of said plate on opposite sides of said last-named slot outlining a recess in which the filler material to be cut can be placed and a lid pivotally mounted on said plate to be closed over the tops of said bars as said plate starts its rearward movement for closing said recess to retain the

filler material in position therein during forward and rearward movement of said plate to insure cutting of the filler material by the knife.

2. In a machine for cutting filler material for use in shoulder pads and having a table top formed with an elongated slot extended fore and aft of the table top and a continuously rotating disc knife fixedly mounted beneath the table top with a portion of its periphery extended upward through the back end of the slot, a slidably mounted receptor for carrying the filler material to be cut rearward to be engaged and cut by the knife, comprising rails mounted on the top face of the table top on opposite sides of the slot, a plate having its side edges slidably engaged in said rails to be slid rearward and forward relative to the knife and normally occupying the space between the knife and the front end of the slot, means for moving said plate rearward and forward, said plate being formed with an elongated slot aligned with the slot of the table top and extended from the rear edge of said plate to a point slightly rearward of the front edge of said plate, bars mounted on the top face of said plate on opposite sides of said last-named slot outlining a recess in which the filler material to be cut can be placed and a lid pivotally mounted on said plate to be closed over the tops of said bars as said plate starts its rearward movement for closing said recess to retain the filler material in position therein during forward and rearward movement of said plate to insure cutting of the filler material by the knife, and bars mounted on the inner face of said lid and shaped to fit into said recess in the closed position of said lid for engaging the filler material to be cut and retain it in position in said recess.

3. In a machine for cutting filler material for use in shoulder pads and having a table top formed with an elongated slot extended fore and aft of the table top and a continuously rotating disc knife fixedly mounted beneath the table top with a portion of its periphery extended upward through the back end of the slot, a slidably mounted receptor for carrying the filler material to be cut rearward to be engaged and cut by the knife, comprising rails mounted on the top face of the table top on opposite sides of the slot, a plate having its side edges slidably engaged in said rails to be slid rearward and forward relative to the knife and normally occupying the space between the knife and the front end of the slot, means for moving said plate rearward and forward, said plate being formed with an elongated slot aligned with the slot of the table top and extended from the rear edge of said plate to a point slightly rearward of the front edge of said plate, bars mounted on the top face of said plate on opposite sides of said last-named slot outlining a recess in which the filler material to be cut can be placed and a lid pivotally mounted on said plate to be closed over the tops of said bars as said plate starts its rearward movement for closing said recess to retain the filler material in position therein during forward and rearward movement of said plate to insure cutting of the filler material by the knife, said pivotal mounting of said lid including resilient means for urging said lid into an open position, and a latch member pivotally carried by said plate and engaging said lid for securing said lid in its closed position.

4. In a machine for cutting filler material for use in shoulder pads and having a table top formed with an elongated slot extended fore and

aft of the table top and a continuously rotating disc knife fixedly mounted beneath the table top with a portion of its periphery extended upward through the back end of the slot, a slidably mounted receptor for carrying the filler material to be cut rearward to be engaged and cut by the knife, comprising rails mounted on the top face of the table top on opposite sides of the slot, a plate having its side edges slidably engaged in said rails to be slid rearward and forward relative to the knife and normally occupying the space between the knife and the front end of the slot, means for moving said plate rearward and forward, said plate being formed with an elongated slot aligned with the slot of the table top and extended from the rear edge of said plate to a point slightly rearward of the front edge of said plate, bars mounted on the top face of said plate on opposite sides of said last-named slot outlining a recess in which the filler material to be cut can be placed and a lid pivotally mounted on said plate to be closed over the tops of said bars as said plate starts its rearward movement for closing said recess to retain the filler material in position therein during forward and rearward movement of said plate to insure cutting of the filler material by the knife, said pivotal mounting of said lid including resilient means for urging said lid into an open position, and a latch member pivotally carried by said plate and engaging said lid for securing said lid in its closed position, and a stop bar mounted on the table top at the front end of the slot in the table top for limiting forward movement of the receptor.

5. In a machine for cutting filler material for use in shoulder pads and having a table top formed with an elongated slot extended fore and aft of the table top and a continuously rotating disc knife fixedly mounted beneath the table top with a portion of its periphery extended upward through the back end of the slot, a slidably mounted receptor for carrying the filler material to be cut rearward to be engaged and cut by the knife, comprising rails mounted on the top face of the table top on opposite sides of the slot, a plate having its side edges slidably engaged in said rails to be slid rearward and forward relative to the knife and normally occupying the space between the knife and the front end of the slot, means for moving said plate rearward and forward, said plate being formed with an elongated slot aligned with the slot of the table top and extended from the rear edge of said plate to a point slightly rearward of the front edge of said plate, bars mounted on the top face of said plate on opposite sides of said last-named slot outlining a recess in which the filler material to be cut can be placed and a lid pivotally mounted on said plate to be closed over the tops of said bars as said plate starts its rearward movement for closing said recess to retain the filler material in position therein during forward and rearward movement of said plate to insure cutting of the filler material by the knife, said pivotal mounting of said lid including resilient means for urging said lid into an open position, and a latch member pivotally carried by said plate and engaging said lid for securing said lid in its closed position, and a stop bar mounted on the table top at the front end of the slot in the table top for limiting forward movement of the receptor, said latch member including a downwardly sloped tail for engaging said stop bar as said receptor approaches its full front position to pivot said latch member

to an inoperative position freeing said lid to be urged to its open position by said resilient means.

6. In a machine for cutting filler material for use in shoulder pads and having a table top formed with an elongated slot extended fore and aft of the table top and a continuously rotating disc knife fixedly mounted beneath the table top with a portion of its periphery extended upward through the back end of the slot, a slidably mounted receptor for carrying the filler material to be cut rearward to be engaged and cut by the knife, comprising rails mounted on the top face of the table top on opposite sides of the slot, a plate having its side edges slidably engaged in said rails to be slid rearward and forward relative to the knife and normally occupying the space between the knife and the front end of the slot, means for moving said plate rearward and forward, said plate being formed with an elongated slot aligned with the slot of the table top and extended from the rear edge of said plate to a point slightly rearward of the front edge of said plate, bars mounted on the top face of said plate on opposite sides of said last-named slot outlining a recess in which the filler material to be cut can be placed and a lid pivotally mounted on said plate to be closed over the tops of said bars as said plate starts its rearward movement for closing said recess to retain the filler material in position therein during forward and rearward movement of said plate to insure cut-

ting of the filler material by the knife, said pivotal mounting of said lid including resilient means for urging said lid into an open position, and a latch member pivotally carried by said plate and engaging said lid for securing said lid in its closed position, and a stop bar mounted on the table top at the front end of the slot in the table top for limiting forward movement of the receptor, said latch member including a downwardly sloped tail for engaging said stop bar as said receptor approaches its full front position to pivot said latch member to an inoperative position freeing said lid to be urged to its open position by said resilient means, and means adjustably mounting said stop bar on the table top.
